WILLIAM M. KECK, OF COALINGA, CALIFORNIA, ASSIGNOR TO SAMUEL ALLEN
GUIBERSON, JR., OF COALINGA, CALIFORNIA.

WELL-CASING HANGER.

1,051,501.

Specification of Letters Patent. Patented Jan. 28, 1913.

Application filed October 8, 1912. Serial No. 724,587.

To all whom it may concern:

Be it known that I, WILLIAM M. KECK, a citizen of the United States, residing at Coalinga, in the county of Fresno and State of California, have invented certain new and useful Improvements in Well-Casing Hangers, of which the following is a specification.

My invention relates, in general, to well-boring apparatus, and, in particular, to hangers for suspending the casing-pipe, and lowering it as the hole is made by the drilling tools.

My invention consists in the novel improved hanger for well-casings, which I shall hereinafter, together with its objects and use, fully describe by reference to the accompanying drawings in which—

Figure 1 is a perspective view, broken, of my improved well-casing hanger. Fig. 2 is a section of the clamp-block. Fig. 3 is a plan of the same.

1 is the casing-pipe, here shown as suspended with its upper end exposed above the well.

2 is a clamp of that form known in the art as a "spider." It comprises a block with a central downwardly tapered hole, and a set or series of toothed dogs 3 termed "slips." The hole in the spider-block is sufficiently large for casing-pipes of largest diameter, and the sets of slips are made of different thicknesses for use with different sized pipes. The engagement of the spider with the casing-pipe is effected in the usual manner, namely by fitting the spider-block over the pipe and dropping the slips in annular series into the tapering hole of the spider block, with the toothed faces of the slips against the pipe. The casing-pipe may thus be firmly gripped about and upon its plain surface at any point below and independent of the coupling collar 4 on its upper end. The spider block 2 is formed with side lugs 5. Over these lugs are freely fitted the slotted lower ends 6 of hanger-bars

7, said ends being held on the lugs by outside collars 8 secured to said lugs. The hanger-bars 7 extend upward a distance, say, in practice, about thirty-five feet, and their upper ends are fitted with a cross head 9 upon which is the link 10 which is engaged by the link 11 in the base of the casing-block 12.

13 indicates the drilling cable or line which goes down into the casing pipe and

carries the drilling tools on its lower end. 14 are safety-chains hooked at their upper ends over the collar 4 and adjustably linked at their lower ends through eye bolts 15, in the spider-block. These insure against any possible relative slipping of the spider and block.

Sufficient is now illustrated to understand my improved hanger. More illustration is therefore unnecessary and would merely confuse. Those skilled in the art will know that the casing-block 12 is suspended by lines which lead up over pulleys in the crown block of the derrick and thence down to the calf-wheel or drum, by the proper manipulation of which the casing pipe is lowered as the hole is made. Also that the drilling cable or line passes up over the crown block pulley and down to the bull-wheel drum which provides for paying out and controlling said line, and that said line is further equipped with the usual "temper-screw," a device which adjustably clamps the line at successive points and provides for its descent in successive stages, and finally, that said "temper-screw" is engaged and operated by the usual "walking beam" by which the successive lift and drop of the drilling tools are effected. All these are usual parts of a drilling outfit, and as I have stated are not necessary to be shown for a clear understanding of my improvement.

In well drilling the casing-pipe is suspended by means which provide for its periodic lowering as the hole is made by the drilling tools which are suspended and operated by the drilling line 13 passing down through the casing-pipe 1. The customary means for suspending the casing pipe is by a device termed in the art an "elevator". 95 This invariably hangs the pipe by engagement under its coupling collar 4. Such engagement is found in practice to entail the following disadvantageous result: It so holds said collar, that when the succeeding section of casing-pipe is screwed down into the collar, said collar will not give or turn on its pipe to make a surer and tighter joint. The collar is seldom initially so fitted to its pipe that, under the increased leverage of 105 screwing in the next pipe section, it will not turn down tighter. This extra turning is of advantage in insuring a tight joint. But, it will be seen, any clamping device such as an "elevator" which directly engages the 110

collar and thereby holds it from further turning down is not good. This difficulty is obviated by the employment of a clamp which does not engage the collar, but directly engages the pipe below the collar, thereby leaving the collar free to make its additional turn or turns. Such a clamping device is found in the spider 2, as I have shown. But, this is not the whole problem. 10 Any suspending device for the casing pipe must be one which will permit at some point a relative movement between said device and the pipe. The pipe is apt to stick in the hole from time to time, so that it has to be successively lifted and lowered a little. If it finds a sticking point somewhat more obdurate than usual so that it comes to a dead stop when being lowered either in its regular feed or during an attempt to work 15 it down by lifting and dropping, it is obvious that when brought to such stop, the effect upon the hanging parts, the weight of which is considerable, will be to impose upon them a compression strain which they are not arranged to bear, and the consequence is that they will slack up or buckle, and the casing block will turn over. With 20 the usual device or "elevator", above mentioned, as a clamping device under the collar, this difficulty is met by the fact that said elevator itself simply slips down on the pipe and thus compensates for the lost motion. But with a rigidly-clamping device, such as the spider 2 which my invention 25 contemplates using, there can be no slippage between it and the pipe, and such slippage must be found elsewhere. Accordingly, I provide for this by the slotted ends 6 of the hanger-bars 7 which are slidably connected 30 with the spider block 2. These slots are of a length sufficient to enable the operator to

see in ample time that the casing is stuck in the hole and that the slotted hanger-bars 7 are still slipping down, and to stop them by proper use of the controlling mechanism. 45 In brief, I am thus enabled to use a clamp which is independent of the collar on the casing-pipe, and still provide for the necessary relative slippage of parts, and herein lies my invention. 50

I claim:—

1. A well-casing hanger comprising a clamp rigidly engaging the casing-pipe body; hanger-bars; and a sliding connection between said bars and clamp. 55

2. A well-casing hanger comprising a clamp rigidly engaging the casing-pipe body, said clamp having side-lugs; and hanger-bars having slotted lower ends slidably engaging the side lugs of the clamp. 60

3. A well-casing hanger comprising a clamp consisting of a block provided with a downwardly tapering hole to surround the casing-pipe, and dogs fitted in said hole to rigidly clamp the block to the pipe; hanger-bars; and a sliding connection between said bars and the block of the clamp. 65

4. A well-casing hanger comprising a clamp consisting of a block provided with a downwardly tapering hole to surround the 70 casing-pipe, and dogs fitted in said hole to rigidly clamp the block to the pipe; said block having side lugs; and hanger-bars having slotted lower ends slidably engaging the side-lugs of the block. 75

In testimony whereof I have signed my name to this specification in the presence of two subscribing witnesses.

WILLIAM M. KECK.
